CLAIM

The ornamental design for a bicycle clip, as shown and described.

DESCRIPTION

FIG. 1 is a Front view of a bicycle clip showing my new design;

FIG. 2 is a Rear view thereof;

FIG. 3 is a Left side view thereof;

FIG. 4 is a Right side view thereof;

FIG. 5 is a Top plan view thereof;

FIG. 6 is a Bottom plan view thereof;

FIG. 7 is a rear perspective view thereof;

FIG. 8 is a bottom, rear perspective view thereof;

FIG. 9 is a front perspective view thereof; and,

FIG. 10 is a top perspective view thereof.

1 Claim, 10 Drawing Sheets(56)
